UNITED STATES PATENT OFFICE.

JOHN LAWRIE AND DAVID FREDERICK BRAZEL, OF THABANCHU, ORANGE FREE STATE, SOUTH AFRICA.

CATTLE-GUARD.

1,140,171.

Specification of Letters Patent. Patented May 18, 1915.

Application filed March 19, 1913, Serial No. 755,357. Renewed October 21, 1914. Serial No. 867,902.

To all whom it may concern:

Be it known that we, JOHN LAWRIE and DAVID FREDERICK BRAZEL, subjects of the King of Great Britain, residing at Thabanchu, Orange Free State, South Africa, have invented a new and Improved Cattle-Guard, of which the following is a full, clear, and exact description.

Our invention relates to cattle guards 10 adapted to be placed between the rails of a railway track adjacent to a crossing, and at the outer sides of the rails, to deter cattle from taking the direction of the track.

It is a design of our invention to provide 15 a cattle guard having novel guard elements so supported as to have marked instability to the tread of the cattle. It is also a design of our invention to improve in various particulars devices of the indicated character, 20 to the end that efficiency in operation may be promoted, as well as increased durability and economy of manufacture, and to provide elements that may be conveniently and properly assembled in place by unskilled 25 labor.

Reference is to be had to the accompanying drawings forming a part of this specification, in which similar characters of reference indicate corresponding parts in all 30 the views.

Figure 1 is a plan view representing a practical embodiment of our invention; Fig. 2 is an end view on an enlarged scale, with elements in section, for the most part on the 35 indicated line 2—2 of Fig. 1, other parts being broken away; Fig. 3 is an end view of a section of our improved cattle guard, on an enlarged scale, with parts broken out, a track rail being in section on about the line 40 3—3 of Fig. 1; Fig. 4 represents one of the transverse bars that carry the guard elements; Fig. 5 represents one of the transverse bars at the ends of a section; and Fig. 6 is a detail transverse vertical section at an 45 end of one of the transverse end bars, and showing in section a portion of the guard element and the supporting means for the said bar.

In constructing the illustrated example of 50 our invention frame bars 10 are provided, ranging longitudinally of each section of the guard, provided with legs 11 having inwardly bent flanges 12 constituting feet which are secured by lag screws 13 or the 55 like to the sleepers 14 in a proper position

relatively to the track rails 15. The frame bars are formed with a series of vertical slots 16, opening at the tops of the bars, the bottoms of the slots constituting bearings for transverse bars 17. Overlying the frame 60 bars, cap plates 19 are provided, suitably secured as by screws 20 to said frame bars. In addition to the slots, the outer frame bars of the outer guard sections are pierced near the ends, and also at about the center, to 65 provide holes 16^a for receiving additional transverse bars 17^a. The bars 17 are formed with fixed shoulders 21 at each end, spaced apart to receive between them the adjacent frame bar, the transverse bars being thus 70 adapted to be dropped into the slots 16 and to be removed therefrom when the cap plate 19 is removed. The bars 17^a on the other hand, have at one end the fixed shoulders 21^a and at the opposite end an inner, fixed 75 shoulder 21^b, the extreme end adjacent to the shoulder 21^b being threaded as at 21^c, to receive a nut 21^d, the threaded portion of the bar being desirably pierced to receive a cotter pin 21^e for fastening the nut. Thus the 80 bars 17^a may be dropped into slots in an inner frame bar 10, and the opposite end is adapted to be passed through a hole 16^a, and then to receive a nut 21^d, the nuts thus serving to clamp the transverse bars in the frame 85 bars.

Each transverse bar 17, 17^a, carries its complement of separate guard elements 18 strung thereon; each guard element is provided with a series of radial projections, desirably in the form of pyramidal spurs 18^a, and the body of a guard element is in the form of a ring, the inner diameter of the bore of which is materially greater than the diameter of the transverse bars, so that the 90 ring freely hangs eccentrically on a bar and is adapted to have a swinging movement in either direction transversely of the transverse bar, and toward and from the guard elements on an adjacent bar; similarly the 95 guard may bodily rise vertically, the various movements thus permitted the guard elements contributing to increase the instability of the said elements to the tread of cattle.

Having thus described our invention, we 100 claim as new and desire to secure by Letters Patent:—

1. A cattle guard, comprising longitudinal frame bars forming the sides of the guard and having legs thereon formed with secur- 110

ing flanges constituting feet, said bars being formed at intervals between their ends with vertical slots extending through the tops of the bars and forming bearings at the bottom, one of the bars being furthermore pierced near the ends, thus presenting holes below the top of the bar, the holes being substantially in the horizontal plane of the bearings at the bottoms of the slots; transverse bars of substantially round cross section extending between the frame bars, certain of the transverse bars being received at one end in the adjacent slots of the frame bars and formed at said end with a pair of fixed shoulders spaced to receive a frame bar therebetween; and at the opposite ends with an inner fixed shoulder and with a threaded end adapted to pass through the mentioned holes of the adjacent frame-bar, the threaded ends being provided with nuts to clamp the frame bars; the intermediate transverse bars having at both ends pairs of fixed shoulders spaced to receive the frame-bars therebetween, those portions of the intermediate transverse bars between the fixed shoulders being adapted to the adjacent slots, to be dropped thereinto, and to be lifted therefrom; cap plates overhanging the tops of the frame-bars and closing the ends of

the slots; fastening devices for securing the cap plates to the frame bars; and removable rings provided with radiating spurs, the rings being loosely hung along the length of the transverse bars and having an inner diameter or bore materially larger than the diameter of the transverse bars, the rings being adapted to swing transversely of the transverse bars in one direction and to rise bodily on the said transverse bars.

2. A cattle guard, comprising side members, transverse bars supported by said side members and spaced from each other, and guard elements mounted on the transverse bars, the guard elements each consisting of a ring having a bore of a diameter materially greater than the diameter of the bar, the rings freely and eccentrically hanging on the bar to swing transversely thereof in either direction and being free to be moved bodily in a vertical direction.

In testimony whereof we have signed our names to this specification in the presence of two subscribing witnesses.

JOHN LAWRIE.

DAVID FREDERICK BRAZEL.
